UNITED STATES PATENT OFFICE

97,465

DESIGN FOR A CONTAINER CLOSURE

Benjamin F. Conner, West Hartford, Conn., assignor to Colt's Patent Fire Arms Manufacturing Co., Hartford, Conn., a corporation of Connecticut

Application March 7, 1935, Serial No. 55,764

Term of patent 14 years

To all whom it may concern:

Be it known that I, Benjamin F. Conner, a citizen of the United States, residing at West Hartford, in the county of Hartford and State of Connecticut, have invented a new, original, and ornamental Design for Container Closure, of which the following is a specification, reference being had to the accompanying drawing.

Of the drawing:

Fig. 1 is a side view of a container closure embodying my new design.

Fig. 2 is a top view.

I claim:

The ornamental design for a container closure as shown.

BENJAMIN F. CONNER.
